UNITED STATES PATENT OFFICE.

WILLY NAUMANN, OF BIELEFELD, GERMANY.

CASH REGISTER.

Application filed December 8, 1923. Serial No. 679,380.

To all whom it may concern:

Be it known that I, WILLY NAUMANN, a subject of Germany, and residing at Bielefeld, Germany, have invented certain new and useful Improvements in or Relating to Cash Registers, of which the following is a specification.

My invention relates to improvements in cash registers, and more particularly in cash registers of the type in which the printing mechanism is adapted to be operated at will for giving out one or two checks or receipts by causing the same to make one or two revolutions, and the object of the improvements is to provide a cash register in which the printing mechanism is operated in such a way that upon a single rotation of the printing mechanism one or two checks or receipts are given out.

For the purpose of explaining the invention an example embodying the same has been shown in the accompanying drawings, in which the same reference characters have been used in all the views to indicate corresponding parts. In said drawings,

Fig. 1, is a partial elevation of the cash register with the parts of the printing mechanism in the positions for giving out one receipt,

Fig. 2, is a similar elevation showing a part of the printing and paper feeding mechanism, the parts being in the positions for giving out two receipts,

Fig. 3, is a similar elevation showing particularly the means for setting the paper feeding apparatus into position for feeding one or two checks,

Fig. 4, is a detail view showing the mechanism for cutting the strip of paper into checks,

Figs. 5 and 6, are detail views showing parts of the gearings intermediate the cash register operating and printing mechanisms, said gearings causing respectively one or two operations of the printing mechanism upon one operation of the cash register, and

Fig. 7, is a detail view showing the means for printing a record on a web of paper remaining in the register.

To a shaft 1 a gear wheel 2 is secured which is adapted to transmit rotary movement through the intermediary of gear wheels 3, 4, 5, 6, 7 and 8 to a shaft 9 carrying two disks 10 and 11 formed with cam grooves engaged by rollers 12^a and 13^a of levers 12 and 13 having bifurcated ends

straddling the shaft 9. At their free ends the rods 12 and 13 are provided each with a notch 121 and 131 respectively, which notches are adapted for alternate engagement with a roller 14^a of a printing member 14 in the form of a bell crank lever having a rocking support on a pivot bolt 15. Figs. 5 and 6 show the levers 12 and 13 and the member 14 controlled thereby in detail. As shown in the said figures the cam grooves are constructed in the disks 10 and 11 in different ways, the groove of the disk 10 comprising a concentric portion 10^a extending over about two thirds of the circumference and an eccentric portion 10^b extending substantially over one third of the circumference, while in the disk 11 the portion of the cam groove which corresponds to the concentric portion 10^a of the groove of the disk 75 10 comprises an eccentric part 11^b extending over about one third of the circumference, so that the groove of the disk 11 comprises two eccentric portions 11^b connected by concentric portions 11^a, 11^a. Therefore 80 the disk 10 is adapted upon each rotation to impart a single printing movement to the member 14, while the disk 11 is adapted upon each rotation to impart thereto two printing movements. On a bolt 16 a bell 85 crank lever 17 is mounted the downwardly directed arm of which carries a pivot block 17^a embraced by the bifurcated part of a lever 18^a of a roll measuring or cutting member 18 (Fig. 4). The upwardly directed 90 arm of the bell crank lever 17 is formed at its end with two shoulders 17^b and 17^c co-operating each with two rollers 4^a, 4^a and 5^a, 5^a respectively mounted on the gear wheels 4 and 5. By thus providing two 95 rollers 4^a and 5^a on each gear wheel 4 and 5 the roll measuring apparatus 18 is twice operated upon each operation of the cash register.

Internally of the cash register there are 100 a setting member 19 rigidly connected with a cam disk 20, and a rock arm 21 mounted on a bolt 21^c, as is best shown in Fig. 3. Substantially at the middle of the said arm there is a roller 21^a engaging in a cam slot 105 20^a of the cam disk 20 having a concentric and an eccentric portion. At its free or bottom end the lever 21 carries a bolt 21^b projecting outwardly through the wall of the casing and engaging in a slot 22^a of an 110 arm 22 rockingly mounted with a slot 22^b provided at its top end on a bolt 23. Near

the slot 22^a and at the right hand side the arm is formed with a nose 22^c. The bottom end of the arm 22 is formed with a hook 22^d adapted for engagement with a roller 24^a of a rock arm 24 mounted on a shaft 25 and rigidly connected by a sleeve 26 with two similar levers 27 located so as to cover each other when looking from the side of the machine, and carrying at their ends a rubber roller 28 forming a part of the mechanism for feeding a strip of paper to the printing mechanism.

On a bolt 29 a bell crank lever 30 is mounted the bottom end of which cooperates with the nose 22^c of the arm 22, while the upper arm carries a roller 30^a bearing on a cam disk 5^b rigidly connected with the gear wheel 5 by a spacing sleeve 5^c. On a bolt 31 a sleeve 32 is mounted the ends of which have arms 33 and 34 rigidly secured thereto (Fig. 2). The lever 33 is curved upwardly and its curved part engages the bolt 21^b. The other lever 34 carries at its end two rollers 34^a and 34^b supporting respectively the rods 12 and 13.

On the outmost type cylinder 35 of the printing apparatus a holder 36 for an inking pad 37 is rockingly mounted. A bifurcated arm 38 rockingly mounted at 38^b engages a roller 36^c of the inking pad holder 36, and, substantially at its middle, it carries a roller 38^a engaging in the cam groove of a disk 39 loosely mounted on a shaft 40. The shaft 40 carries a gear wheel 41 rigidly connected with the disk 39, a cam 42 cooperating with a printing foot lever 43, and a driving wheel 44 keyed or otherwise secured to the shaft and adapted to transmit rotary movement to a gear wheel 47 keyed to a feed roller 48 through the intermediary of gear wheels 45 and 46. Within a paper guide 49 a strip of paper 50 is guided between rollers 48 and 28 to a knife 18.

The driving gear wheel 44 and the gear wheel 45 are connected with a suitable gearing for transmitting intermittent movement to the gear wheel 41, the cam disk 39 and the cam 42 for moving and arresting the said parts at certain periods in the operation of the mechanism. Mechanism of this kind is known in the art and has therefore not been illustrated in the drawings.

On the shaft 40 a spool 59 having a strip of paper wound thereon is loosely mounted, and a strip of paper 51 taken therefrom is passed between the printing foot 43^a and inking pad 37 to a spool 52 for winding the same, the spool 52 being intermittently rotated by means of a pawl 53.

The operation of the mechanism is as follows: It may be assumed that the setting member 19 is shifted two steps from the position shown in Fig. 1. The cam disk 20 connected with the setting member takes part in such movement and the roller 21^a is

advanced relatively to the cam disk 20 through the concentric part of the cam slot without shifting the arm 22, which arm embraces the roller 24^a with its notch 22^d, as is shown in Fig. 1. The lever 12 remains in engagement with the roller 14^a of the printing foot lever 14. When operating the cash register the cam disk 10 causes a single printing operation of the lever 14. The feeding portion 48^a of the feed roller 48 advances the check strip 50 a certain distance for being cut by the knife 18, whereupon the roller 30^a of the lever 30 leaves the concentric part of the cam groove of the disk 5^b, and the nose 22^c of the rod 22 is forced upwardly by the said lever, and the roller 28 is rocked away from the feed roller 48, so that the second feeding portion 48^a of the feed roller is inoperative and a single check is given out, the second cutting operation of the knife 18 being ineffective, because the strip of paper has not been advanced after the first cutting operation.

If, however, the setting member 19 is set into the position IV, the roller 21^a moves within the eccentric portion of the cam groove 20^a to the left and it throws the arm 22 by means of the bolt 21^b out of engagement with the roller 24^a of the lever 24, as is shown in Fig. 2. By rocking the lever 21^b to the left the lever 33 is forced downwardly and the lever 34 connected therewith is rocked upwardly, so that the rollers 34^a and 34^b lift the rods 12 and 13 so far that the rod 12 releases the roller 14^a, and the rod 13 gets into engagement with the roller 14^a.

Upon operation of the machine the cam disk 11 causes two printing operations to be successively performed, and the first and second feeding portions 48^a are operative because the notch 22^d of the lever 22 is out of engagement with the roller 24^a, so that the roller 28 is relieved of the pressure holding the same in engagement with the feeding disk 48. Therefore two checks having the same record printed thereon are given out.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

I claim:

1. In a cash register the combination, with the printing mechanism, operating mechanism, mechanism intermediate said operating mechanism and printing mechanism adapted when actuating the operating mechanism to transmit to the printing mechanism respectively one and two print-

- ing operations, and means to set said transmitting mechanism into position for causing one or two printing operations, of paper feeding apparatus operatively connected 35
5 with said operating mechanism for receiving therefrom two feeding operations, means to render said feeding apparatus inoperative during one feeding operation, and means for cutting checks from said paper. 40
10 2. In a cash register the combination, with the printing mechanism, operating mechanism, transmission gearings intermediate said operating mechanism and printing mechanism adapted when actuating the 45
15 operating mechanism to transmit to the printing mechanism respectively one and two printing operations, and means to set either one of said transmission gearings into operative position, of means for feeding and cutting a strip of paper. 50
20 3. In a cash register the combination, with the printing mechanism, operating mechanism, transmission gearing intermediate said operating mechanism and printing mechanism and comprising two levers adapted for alternate engagement with the printing mechanism and connected with the operating mechanism for receiving therefrom respectively one and two movements, 55
25 and means to set either one of said levers into position for engagement with the printing mechanism, of mechanism for feeding a strip of paper into printing position and connected with said operating mechanism for receiving therefrom two operations upon one operation of the operating mechanism, means connected with one of said levers for rendering said feeding mechanism inoperative during one feeding operation, and means for cutting checks from 60
30 said strip of paper.

In testimony whereof I hereunto affix my signature in the presence of two witnesses.

WILLY NAUMANN.
